(57) **CLAIM**

The ornamental design for keyboard dock, as shown and described.

DESCRIPTION

FIG. 1 is a front, top, right axonometric view of a keyboard dock showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines illustrate portions of an electronic device, in which the inventors embody the claimed design, and form no part of the claimed design.
